[57] CLAIM

The ornamental design for a boat steps, as shown and described.

DESCRIPTION

FIG. 1 is a left rear perspective view of boat steps, showing my new design, an overhanging boat transom being shown in broken line for illustrative purposes only;

FIG. 2 is an elevational view of one side, the other side being in mirror symmetry;

FIG. 3 is a median sectional view, the plane of the section being indicated by the line 3—3 in FIG. 4;

FIG. 4 is a rear elevational view;

FIG. 5 is a top plan view;

FIG. 6 is a bottom plan view; and,

FIG. 7 is a front elevational view.
